(57) **CLAIM**

The ornamental design for a contour gauge, as shown and described.

DESCRIPTION

1. Contour gauge

1.1 : Front

1.2 : Bottom

1.3 : Right

1.4 : Top

1.5 : Left

1.6 : Back

1.7 : Perspective

A contour gauge for copying and marking a variety of angles and odd shapes; it creates a template for marking precise cuts to conform to shapes and edges and which holds their pattern with the help of a lock.
